UNITED STATES PATENT OFFICE.

HOWARD B. EVANS, OF PORTLAND, OREGON.

MIXING MACHINE FOR CONCRETE MIXTURES AND THE LIKE.

Application filed September 27, 1922. Serial No. 590,902.

To all whom it may concern:

Be it known that I, HOWARD B. EVANS, a citizen of the United States of America, and a resident of Portland, in the county of 5 Multnomah, in the State of Oregon, have invented certain new and useful Mixing Machines for Concrete Mixtures and the like, of which the following is a specification, reference being had to the accompanying drawings.

My invention relates to that class of machines which are ordinarily denominated concrete mixers, and has for its main object, among others, the production of such a machine which is adapted to receive material supplied to the mixing chamber, and to make discharge thereof from either side of the machine at the will of the operator, or to receive said material on one side of the 10 machine and make discharge thereof on the other; which is adapted to effect operation of the mixing-chamber with its axis disposed at variable angles, and within all practicable bounds, irrespectively of the plane in 15 which the supporting frame of the machine is disposed; which is contrived for ease and facility of manipulation in respect to the performance of all its functions which require manipulative direction or control; and 20 which is light in weight and conveniently 25 movable from place to place.

An important feature of my invention also consists in the provision of a machine in which all its driving parts are completely 30 operative independently of the presence or absence of the mixing-chamber. By this means provision is made for the mounting or 35 demounting of the mixing-chamber from the machine without disturbing the assembly- 40 ment of the mechanical working parts.

My machine, within the scope of the foregoing general description and as hereinafter specified in detail, possesses an extraordinary efficiency or capacity for work in proportion 45 to its size and to the cost of manufacture. At the same time, its simplicity of construction contributes materially to the economy of its maintenance and cost of operation.

What constitutes my invention will be 50 hereinafter specified in detail and succinctly set forth in the appended claim.

In the accompanying drawings, in which my invention is illustrated in present preferred form of embodiment,

55 Figure I is a front elevation of my machine, showing the mixing-chamber tilted

for the discharge of its contents to one side of the machine.

Figure II is a similar view, showing the mixing-chamber in one position for mixing 60 operation which is also adapted for receiving a charge of material to be mixed from the side of the machine opposite to that towards which it is shown as discharging in 65 the preceding figure.

Figure III is a rear elevation of my machine substantially in the position of its parts shown in Figure I.

Figure IV is a top plan of my machine, showing the mixing-chamber with its longitudinal axis in horizontal disposition.

Figure V is a side elevation of the machine as shown in Figure IV, looking towards the bottom of the mixing-chamber.

Figure VI is an edge elevation of the mixing-chamber tilting-lever of my machine detached from the machine, the quadrant with which it coacts being shown in section.

Referring to the numerals on the drawings, 1 indicates a rear axle with which my machine is provided for the accommodation of a pair of supporting wheels 2.

From the axle 1 extends a medially disposed tongue 3, and an oblong rectangular frame 4, which may be to advantage constructed of angle iron. The frame 4 is provided, adjacent to its forward corners, with legs 5, which are united, respectively, to the tongue 3, as by braces 6. The tongue preferably terminates in a hitch-ring 7, by 90 which it may be fastened to a vehicle for hauling it about from place to place as occasion may require.

Upon a cross-piece 8 of the frame 4 is firmly mounted an upright frame 10, and 95 near the opposite end of the frame 4, as upon a cross-piece 11, is mounted an upright frame 12, corresponding to the frame 10.

Carried in the upper portions of the frames 10 and 12, respectively, are suitably 100 journaled, oppositely extending, coaxial shafts 14 and 15, whose opposing ends are fixed to side bars 16 and 17, respectively. The said side bars constitute the side of a preferably rectangular loop, which is completed below by a bottom-plate or cross-over 18, and which is surmounted by a square frame 19 to which the loop is securely attached, in order to constitute a tilting-frame.

Within the frame 19 is securely confined a 110 mixing chamber 20, whose bottom is supported by a flanged sleeve 21 interposed be-

tween it and the cross-over 18 (see Figure IV). The said chamber preferably consists of a stout wooden barrel, which is provided on its inside with fixed plates 23, whose respective longitudinal axes are parallel to the longitudinal axis of the barrel. My preference for the use of a barrel as a mixing-chamber is due to the fact that it is desirable to construct said chamber of wood rather than metal as a preventative against adhesion of the concrete mixture to the side of the chamber. The use of a barrel also affords means for its renewal whenever occasion may require, with minimum loss of time.

15 Within a housing 25, preferably located over the axle 1, is mounted any suitable motor, not necessary to illustrate, whose power shaft 26, that is provided with an outside fly-wheel 27, if desired, terminates in a driving pinion 28. The pinion 28 is geared, as by a sprocket belt 30, to a gear 31, fixed to a sleeve 29 upon the shaft 14, and is adapted to impart transverse rotation to the barrel 20 through rotation upon its supporting shafts 14 and 15 of the frame which comprises the side bars 16 and 17.

Within the frame last named, the barrel 20 is securely mounted so that it may rotate about its longitudinal axis. To that end it is provided, in a plane nearer to its open end, with an annular hoop-like track 32, which is preferably circular in cross-section, and is securely fixed to the circumference of the barrel. With the said track, upon opposite sides of the barrel, respectively, engage, with rolling contact and barrel-supporting effect, a pair of grooved rollers 33 and 34, which are each adjustably supported upon the frame 19, as by journal boxes 35 and 36, respectively. By aid of the adjustment of the four rollers 33 and 34, the longitudinal axis of the barrel may be made by adjustment to coincide with the axis of the sleeve 21.

45 Within the sleeve 21 is provided a shaft 38 fixed to the sleeve and by it to the bottom of the barrel. The shaft 38 works in a bearing provided for it in the bottom of the plate 18 and carries a bevel gear 39 fixed to it. The gear 39 meshes with a bevel pinion 40, which is fixed to a shaft 41 carried in bearings 42 secured to the bottom plate 18. By aid of a gear 43 fixed to the shaft 41, a gear 44 fixed to the sleeve 29, and an intermediate sprocket chain 45' operatively uniting said gears, the barrel is adapted, in all positions of the side bars 16 and 17, relative to the axes 14 and 15, to be rotated about its longitudinal axis, with mixing effect upon the contents of the barrel. It may be observed that said rotative motion of the barrel may be accomplished while the barrel is in any relative position in respect to the axle 1, for example, and that the rotation 65 of the barrel may be thereby made effective

either for mixing purposes, or for aiding, when the barrel is sufficiently tilted, the discharge of the contents thereof.

In order to effect, upon occasion, the tilting of the barrel 20, I provide upon the outer end of the shaft 15 a lever 45, which is in effect a double lever, extending as it does equidistantly upon opposite sides of the said shaft to which it is fixed. Said lever preferably terminates at one end in a hook 46 adapted to overhook a quadrant 47 fixed to the upright frame 12. Adjacent to each end of the lever 45 is a handle 48 which extends substantially at right angles to the lever. The handle adjacent to the hook 46 carries a bent lever 49, whose long arm extends in a grasp disposed in operative proximity to the handle 48 it serves, and whose short arm actuates a stop-pin 50. Each stop-pin is adapted to reciprocate to and from the quadrant 47 so as to engage or disengage one of two series of pin-holes 51 provided at opposite ends, respectively, of the quadrant. A leaf spring 52 on the lever 45 serves, by engagement with the lever 49, to actuate that lever and the pin 50 fastened to the end of the spring as shown in Figure VI.

I prefer to provide means for assisting in the tilting of the barrel in either direction when it is loaded, in order to relieve the operator in the manipulation of it and so as to throw it laterally in either direction. A simple means for the purpose indicated is found in a coiled tensile spring 53 loosely fastened at one end to the barrel supporting frame as indicated at 54, and fastened at the other end, preferably in like manner, to the tongue as indicated at 55.

The operation of my machine may be briefly described as follows. After it is placed in position desired for doing its work, the open end of the barrel being, for example, in the position shown in Figure II, material to be mixed is supplied to the interior of the barrel. During such filling operation the machine may continue in motion, or it may be stopped for the occasion and afterwards set in motion if desired. After the barrel is supplied with a charge to be mixed, it may be set so that its axis is in vertical position, but that is not necessary since the barrel may be effectively rotated, for mixing purposes, in any position in which, during its rotation, it will hold its contents without spilling.

In swinging the barrel from one position to another, as, for example, from that shown in Figure II to that shown in Figure I, the operator grasps with one hand the handle of the lever 45 that is uppermost, and the other handle with the other hand. Then, upon release from the quadrant of the handle 48 that is in engagement therewith, by a pull upon one handle and a push upon the other, the tilt of the barrel and its supporting

frame may be adjusted to the desired angle, and be there secured by engagement of a stop-pin 50 with one of the pin-holes 51 that is within available reach of said pin.

5 In swinging the barrel frame from one position to another as above specified, the power of the spring 53 becomes available to compensate materially against the inertia or the weight of the load of the barrel, 10 while the momentum gained by the swinging of the barrel readily overcomes the power of the spring so as to stretch it, if necessary, and in effect to interpose it against shock, after the manner of a yielding buffer.

15 What I claim is:

In a mixing machine of the kind described, the combination with a supporting frame, supporting members thereon, a tilting-frame

comprising side pieces, and opposite supporting shafts operatively connecting said side pieces and the supporting members, of means for rotating a mixing-chamber carried in the tilting-frame independently of the tilting of said frame, means for adjustably tilting the tilting-frame in opposite directions, and a compensating tensile spring attached at one end to the tilting-frame and at the other end to the supporting frame. 20 25

In testimony whereof, I have hereunto set my hand in the presence of two subscribing 30 witnesses.

HOWARD B. EVANS.
